(57) **CLAIM**

The ornamental design for a mobile phone display screen with graphical user interface, substantially as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a mobile phone display screen with graphical user interface, showing our new design.

FIG. 2 is a second image thereof; and,
FIG. 3 is a third image thereof.

The appearance of the aminated graphical user interface transitions sequentially between FIGS. 1-3. The process or period in which one image transitions to another forms no part of the claimed design.

The broken lines showing an electronic device and display screen illustrate portions of the article, and form no part of the claimed design.
